UNITED STATES PATENT OFFICE.

LOUIS WEISSENBORN, OF PASADENA, CALIFORNIA.

DESIGN FOR A CHAIR.

60,763.

Specification for Design. Patented Apr. 4, 1922.

Application filed June 27, 1921. Serial No. 480,941. Term of patent 3½ years.

To all whom it may concern:

Be it known that I, LOUIS WEISSENBORN, a citizen of the United States of America, residing at the city of Pasadena, in the county of Los Angeles and State of California, have invented a new, original, and ornamental Design for a Chair, of which the following is the specification, reference being had to the accompanying drawing, forming a part thereof.

The figure is a perspective view of a chair constructed in accordance with my design.

I claim:

The ornamental design for a chair, substantially as shown.

LOUIS WEISSENBORN.
